METHOD AND APPARATUS FOR FORMING
A WIRE TIE

Marchand B. Hall, Olympia Fields, John P. Long, Park Forest, and Edward W. Schultz, Homewood, Ill., assignors to United States Steel Corporation, a corporation of Delaware

Filed May 6, 1965, Ser. No. 453,767
5 Claims. (Cl. 140—71)

ABSTRACT OF THE DISCLOSURE

Method and apparatus for producing a tie wire having a ring-secured loop in one end. Apparatus includes a counterbored cylinder having spaced bending pins upstanding on one end thereof. Hook means reciprocable through the counterbore of the cylinder are adapted to engage a length of wire positioned between the bending pins and lying across a ring fitted in the end of the counterbore of the cylinder. The method includes the steps of positioning a length of wire between a pair of fixed bending pegs over a ring, then rotating the pair of pegs to form a substantially Z-shape portion in the wire, and then pulling the formed portion of the wire through the ring.

The present invention relates generally to the art of securing lading on a transport vehicle and, more particularly, to a novel method and apparatus for forming a wire tie especially suitable for securing a load on a railroad flat car equipped with recessed stake pockets.

Prior to our invention, loads to be transported by railroad flat cars were very often secured on the car by a plurality of spaced wire ties anchored to the car on each side thereof and extending over the load transversely of the car. Usually, each wire tie was made up of two lengths of tie wire which were each secured by one end to stake pockets on opposite sides of the car and had their other ends twisted together above the load to form the wire tie.

The anchored ends of the tie wires were in most cases knotted around the outer walls of the stake pockets. When the car was to be unloaded, the wire ties were severed to free the load and the anchored ends of the tie wires were cut away from the stake pocket walls.

The above-described method of anchoring the tie wires to the flat car worked satisfactorily with flat cars having open-bottom stake pockets arranged along the outer edges of the car. However, it was not completely effective for securing loads on modern flat cars which are provided with recessed stake pockets in the floor of the car. On cars of the latter construction, the anchoring ends of the tie wires were knotted around a cross pin which extended transversely of the stake pocket adjacent the bottom thereof. Then, when the tie wires were drawn taut and twisted together by a conventional power tool, the knots at the anchoring ends thereof slipped and drew tightly around the pins in the respective stake pockets. This made it extremely difficult to remove the anchored ends of the tie wires from the stake pockets due to the difficulty of manipulating wire cutters in the narrow confines of the stake pocket to cut the wires free of the pins. As a result, the anchored ends of the wire ties were not removed each time a flat car was unloaded. The ends of the tie wires remained fastened to the stake pocket pin; and, when the car was next loaded, the new tie wires were knotted around the pins adjacent the remains of the previous tie wires. This practice was necessarily limited since there was space for only four or five loops of wire around each stake pocket pin. This condition resulted in serious

difficulties and excessive delays in securing flat car loads with wire ties.

It is, accordingly, the primary object of our invention to provide an improved method and apparatus for forming a wire tie whereby one end of the tie can be anchored to a flat car recessed stake pocket in such a manner as to be easily and readily removable therefrom when desired.

It is a more specialized object of our invention to provide a wire tie having a loop secured by a ring thereover adjacent one end, whereby the one end of the tie can be fastened around a stake pocket pin with a non-slip knot projecting upwardly and outwardly of the stake pocket so as to be easily accessible for cutting and removal.

The above and other objects will become more apparent after referring to the following specification and attached drawings, in which:

FIGURE 1 is a plan view showing a length of tie wire in position in the apparatus of the invention prior to bending thereof and formation of a loop therein;

FIGURE 2 is a view similar to FIG. 1 but showing the tie wire after bending and prior to formation of a loop therein;

FIGURE 3 is a front elevational view of FIG. 1 with parts broken away for clarity;

FIGURE 4 is a view similar to FIGURE 3 but showing the positions of the elements of the invention after a loop has been formed in the tie wire;

FIGURE 5 is a side elevational view with parts broken away for clarity taken substantially along the line V—V of FIGURE 4;

FIGURE 6 is a side elevational view of the ring-secured loop produced by the method and apparatus of the invention;

FIGURE 7 is a bottom view of FIGURE 6;

FIGURE 8 is a front elevational view showing the tie wire with the ring-secured loop formed therein loosely secured to the cross pin of a recessed stake pocket; and

FIGURE 9 is a view similar to FIGURE 8 showing the tie wire of FIGURE 8 after tension has been applied thereto.

Referring more particularly to the drawings, reference numeral 2 designates a base plate rigidly mounted by one edge in horizontal position on a fixed support 4 by nut-and-bolt means 6. Support 4 may be a bench, machine ledge, beam or any other convenient, similar support. The base plate 2 is provided with a circular opening therethrough in which is rotatably mounted, by means of an anti-friction bearing 8, a cylinder member 10 having a center opening 12 extending axially therethrough. The upper end of the center opening 12 is counterbored to provide a recess 14 for receiving a ring member or washer R, the purpose of which will become apparent. A pair of spaced bending pins 16 is upstanding on the upper surface of the cylinder 10 astride the recess 14. A pair of spaced walls 18 is upstanding on the base plate 2 extending tangentially of opposite sides of the upper surface of the cylinder 10.

A hook rod 20 is disposed for axial, reciprocable movement in the center opening 12, with a portion thereof normally projecting above the upper surface of the cylinder 10. The projecting portion of the hook rod 20 is formed with a laterally extending recess 22 for engaging a tie wire W.

The lower end of the cylinder 10 is formed with a diametral slot 24 for accommodating a lever 26 pivoted to the cylinder 10, as at 28, for turning the cylinder. As best shown in FIGURE 3, the lever 26 is provided with a handle projection 30 on one end to facilitate manipulation thereof. A link 32 is pivoted at one end to the hook rod 20 and at its other end to the lever 26 whereby the

hook rod can be moved axially in the center opening 12 by manipulation of the lever 26.

A guide projection 34 extends from the end of the lever 26 opposite the handle 30 and cooperates with a substantially cylindrical wall or skirt 36, which depends from the base plate 2, to control the movement of the lever 26. The bottom of the wall 36 is formed with spaced shoulders 38 and 39 adjacent respective ends thereof of which function as abutments for limiting angular movement of lever 26, and consequently, cylinder 10, to approximately 115 degrees in a plane parallel with the horizontal plane of the base plate 2. A vertical slot 40 is formed in the wall 36 adjacent shoulders 39 for accommodating the guide projection 34 to permit angular movement of the lever 26 in a plane substantially normal to the base plate 2 and consequent reciprocal movement of the hook rod 20 axially in the center opening 12 of cylinder 10.

In operation, to form a ring-secured loop adjacent one end of a length of the tie wire W, a washer R is placed in the recess 14; and a length of pre-straightened and cut tie wire W is laid across the top of the cylinder 10 between the bending pins 16 and between the upstanding walls 18, with the recess 22 of hook rod 20 in engagement with the wire at a point approximately 18 inches from one end. Then the handle 30 is grasped to turn the cylinder 10 and hook rod 20 approximately 115 degrees in clockwise direction from the position shown in FIGURE 1 to the position shown in FIGURE 2. This action causes the portion of the wire overlying the cylinder 10 to be bent into substantially a Z-shape, forming a pair of substantially right-angled bends in the wire connected by a straight portion overlying the washer R, as best shown in FIGURE 2. The upstanding walls 18 cooperate with pins 16 and aid in forming the right-angle bends in the wire. At this point, guide projection 34 is in abutting engagement with the shoulder 39 adjacent slot 40 and aligned with the latter.

The handle 30 is then depressed to pull hook rod 20 downwardly and draw the wire downwardly through the washer R. This action causes the wire to lift off of the bending pins and form a loop L, secured at its base by the washer R, as shown in FIGURES 4 and 6. The handle 30 is then raised, and the length of the tie wire with the washer-secured loop L adjacent one end is removed from the apparatus. The cylinder 10 is then rotated in counterclockwise direction, as viewed in FIGURE 1, by handle 30 and lever 26 until guide projection 34 abuts the shoulder 38 remote from slot 40. The apparatus is then in starting position, ready to receive another length of tie wire to be processed.

To anchor the length of tie wire W to the cross pin P of a stake pocket S recessed in the floor of a flat car, the end E of the wire W adjacent the loop L is first bent around the pin P. Then the end E of the wire is inserted through the loop L. As shown in FIGURE 8, wire end E is then bent around the remainder of the tie wire and again inserted through the loop L after which tension is applied to the tie wire and it is joined to another tie wire

(not shown) over the top of the load (not shown). The knot so formed, as best shown in FIGURE 9, is prevented from slipping or drawing down around the pin P by the loop L and the washer R as tension is applied to the tie wire when it is twisted together with a tie wire anchored on the opposite side of the flat car. Thus, the strands of the knot will always be accessible for cutting and removal from the cross pin P.

While one embodiment of our invention has been shown and described, it will be apparent that other adaptations and modifications may be made without departing from the scope of the following claims.

We claim:

1. Apparatus for forming a loop in a wire and securing it with a ring which comprises a base plate, a cylinder having an upper and lower end sunk through said base plate and rotatable therein, spaced bending pins upstanding from the upper end of said cylinder, said cylinder having a central bore therethrough, a hook rod reciprocable axially in said bore and normally projecting above said upper end so as to engage a length of wire laid thereacross, the lower end of the cylinder having a diametral slot, a lever fitted in said slot and pivoted to said cylinder for turning it, a pair of spaced walls upstanding on said base plate on opposite sides of said cylinder, and a link pivoted to said lever and said rod for actuating the latter.

2. Apparatus for forming a loop in a wire and securing it with a ring as defined by claim 1 in which said lever has a portion projecting beyond the pivotal connection thereof to said cylinder, and a cylindrical wall depends from said base plate and cooperates with said projecting portion to control movement of said lever.

3. Apparatus for forming a loop in a wire and securing it with a ring as defined by claim 2 in which said wall has abutments limiting angular movement of said lever in the plane of said base plate and a slot permitting angular movement of the lever in a plane normal to the base plate.

4. A method of forming a loop in a wire and applying a ring thereover which comprises placing a ring between two spaced rotatable bending pins, then placing a length of wire between said pins in overlying relation to said ring, then rotating said pins thereby forming a pair of spaced, substantially right-angled bends in said wire connected by a straight portion, and then pulling said portion through the ring.

5. A method of forming a loop in a wire and applying a ring thereover as defined by claim 4 including the step of confining the portions of the wire beyond said straight portion while forming said bends.
